SUPERHEATER BAFFLING

Ward S. Patterson and Elmo M. Powell, Chappaqua, N. Y., assignors to Combustion Engineering-Superheater, Inc., a corporation of Delaware

Original application October 20, 1943, Serial No. 506,922. Divided and this application February 28, 1946, Serial No. 650,971

2 Claims. (Cl. 122—480)

1

This invention relates to improved superheater installations for steam generating units.

As contemplated herein a superheater installation includes, besides the heat transfer surface, means for confining the gases within the superheater space, for directing the gases over the heating surface in the desired manner, and for controlling the quantity of gas flowing over the superheater. Superheaters embodying in some form or other one or more of these features are commonly used on all high pressure, high capacity steam generating units, but this invention relates to several novel changes in the arrangement now known to the art, which will greatly increase performance, economy of manufacture, and life of equipment.

In superheaters for high pressure steam generators, it is common practice to heat the steam to 925° F. or higher. One of the limitations has been the metal available for fabrication of the tubes in which the steam is heated but, as progress in alloy steels proceeds, the more serious limitations may be in other aspects of design. For example, when heating steam to the present high temperatures, there is a definite quantity of heat absorption required for each pound of steam, approximately 270 B. t. u. In a convection superheater, this heat must come from the gases passing over the superheater of which there is a definite quantity, for each pound of steam, of the order of magnitude of 1.2. Therefore, each pound of gas must give up 225 B. t. u. or over, which is equivalent to a temperature drop of approximately 800° F.

The lowest capacity at which a superheater is expected to heat the steam to maximum temperature is called the "control point." In designing for this point, it is desirable to utilize the available heat in the gases in the most efficient manner so as to require the least amount of heating surface in tubes arranged on the widest possible spacing and yet occupying the least possible space and requiring the lowest possible entering gas temperature. The least amount of heating surface under given temperature conditions results from using the highest product of mean temperature difference times gas side heat transfer rate. Obviously, the highest product will result when each of the individual factors is the highest; and, it is well known in the art of heat transfer that it requires counter-flow to result in the highest mean temperature difference and gas flow transverse to the axis of tubes to give the highest heat transfer rate, other things being equal, such as, the power loss resulting from the friction between the gases and the tube surface. It is one of the

objects of this invention to combine both these desirable features in the same arrangement.

When operating a convection superheater at capacities above the "control point," the tendency is for the steam temperature to be higher because of higher gas temperature and one method of preventing this is by decreasing the quantity of gas which is directed over the superheater surface. It is obvious to one skilled in the art that the greatest reduction in steam temperature by this control means can be obtained with the least quantity by-passed if the flow of the by-passed gases is so directed as to completely miss all, or a major portion, of the superheater surface; or, in any event, so as not to come in contact with superheater surface in a manner which would result in a high rate of heat transfer. Obviously any arrangement that permits the by-passed gases to first contact considerable superheater surface in a flow path transverse to the axis of the tubes is defeating the purpose of the by-pass and will seriously limit the amount of temperature control. It is one of the objects of this invention to disclose a method of directing the by-passed gases in the preferred manner, the purpose of which is to decrease the by-passed quantity, the required size of the by-pass, the required size and cost of by-pass damper, and to improve steam temperature control.

Since the by-passed gas does not pass over the superheater surface, it enters the by-pass at high temperature. Furthermore, it is not always possible with arrangements heretofore used to cool the by-passed gases to the same temperature as the main body of gases which has passed over the superheater. This has often resulted in two streams of gases of widely different temperatures, which, without sufficient opportunity to mix, have then been directed over the next section of heating surface of the boiler unit. Very frequently the water heating economizer follows directly after the by-pass damper in the direction of gas flow, and a non-uniform gas temperature and/or velocity entering this equipment is very undesirable. This invention includes a novel arrangement of a superheater and its associated by-pass and by-pass damper, which accomplishes mixing of the two gas streams in a portion of the unit where steam is being generated and where, therefore, the stratification is of minor importance. The arrangement has the added advantage of absorbing heat from the two gas streams while they are being mixed, thereby making more effective use of the installed heating surface and increasing the efficiency of the unit without additional material cost.

In a superheater comprising an adjacent bypass and its associated damper, the resistance of the two parallel flow paths must be such that the desired division of the gas stream can be accomplished. Reduction of the quantity to be by-passed is an important step in the right direction and will result from the application of gas-directing means mentioned above; but the fact remains that when gas is directed through the by-pass, the draft loss in the parallel superheater pass is decreased and, consequently, with the damper design now in common use, the capacity of the by-pass is very limited unless an unusually large by-pass and correspondingly large and expensive damper is provided. Therefore, it is one of the features of the proposed arrangement to locate and pivot the damper in such a way as to add resistance in the superheater pass when the damper is opened and thereby insure that the capacity of the by-pass is not wholly dependent on the proportions of the two parallel gas passes. This novel feature results in a saving in material, expense, and size of equipment, or, alternately, in increased range of superheat control if by-pass and damper are not decreased in size.

The present invention will be best understood upon consideration of the following detailed description of various embodiments when read in conjunction with the accompanying drawings in which:

Figures 1 and 2 are partial sectional elevations of embodiments of the improved superheater and by-pass organization adapted to a steam generator.

This application is a division of that filed in our name on October 20, 1943, under Serial No. 506,922 and which issued on July 2, 1946 as U. S. Patent 2,403,237.

In Fig. 1 of that parent case (now Patent 2,403,237) there is disclosed a steam generating unit the major part of which is located beyond the outlet at the top of the furnace (not here shown) and which includes a bank of tubes 5 (see Fig. 1 hereof) connecting steam and water drum 2 with a water drum (not here shown) therebelow. The bank of boiler tubes 5 is provided at either side with baffles 9 and 10 (see Fig. 1 hereof) so arranged as to cause the gases to flow from the top downwardly along the tubes of said bank. The furnace has its rear wall faced with steam generating tubes 12 some of which are bent to form a screen 13 (see Figs. 1 and 2 hereof) over which the gases from the furnace first pass while others form a second screen 14 spaced outwardly from the first. Preferably all of the walls of the furnace are faced with steam generating tubes. Between the spaced screens 13 and 14 is one section 16 (see Fig. 1 hereof) of the superheater. In the downpass intermediate the screen 14 and the bank 5 is located another part of the superheater, this may be constructed as a single group of parallel tubes interconnected for serial flow of steam through successive tubes and extending for substantially the full length of the pass wherein installed or it may be constructed as shown in two superimposed groups of tubes 18A and 19A connected for series flow of steam therethrough.

The gases leaving the furnace pass (as indicated by Fig. 1 hereof) over screen 13, section 16 of the superheater, screen 14, and thence downwardly along the tubes of superheater sections 19A and 18A. Some of the gases upon entering superheater section 19A may pass thereacross and

enter the top of the steam generating bank 5, thence pass downwardly through said bank to the gas outlet near the base thereof. The gas flow through said bank may be regulated by damper 28 which thus controls a by-pass around the superheater.

From superheater inlet header 24A steam flows downwardly and serially through superheater groups 18A and 19A to the section 16 as indicated by the arrows. It will be noted that the lower group 18A receives the coldest steam which then passes to the upper group 19A to meet the hotter gases before leaving that section of the superheater. In this way partial counterflow of steam and gases is established. From superheater group 19A the steam then passes to superheater section 16 and after passing through this section is delivered to offtake header 25A. In general the gases pass over superheater sections 18A, 19A along or parallel to the superheater tubes. The above described arrangement (as shown by Fig. 1 of our parent Patent 2,403,237) is conventional.

Because the heat transfer rate with gases flowing parallel to the axis of tubes is substantially less than that when flowing across the tubes, the corresponding sections 18A, 19A (Fig. 1 hereof) of our improved superheater are arranged for a flow of the gases transverse to the axis of the superheater tubes throughout the gas path as well as for counterflow of the gases with respect to the steam. Figure 1 hereof shows a partial section of a steam generator and associated superheater with superheater sections 18A and 19A through which the steam from inlet header 24A flows serially as shown by the arrows to leave the unit by way of outlet header 25A. The steam leaving the front of section 18A is conveyed by tubes 26 to tubes at the rear of section 19A. The tubes 26 extend between the two sections and across from the front to the rear thereby forming a support for a special baffle 27 mounted intermediate and separating the sections. Baffle 27 is spaced forwardly from bank baffle 9 and extends forwardly to meet a baffle 28 mounted on a row of furnace tubes which are spaced forwardly with respect to the section 18A to form a gas chamber 31. At about the middle of section 18A a finger baffle 29 extends from the forward bank baffle 9 toward the front side of section 18A. By this arrangement, the furnace gases enter the upper section 19A, flow transversely of the tubes, and in counterflow with respect to the steam flowing through the tubes thence pass downwardly and transversely over the upper portions of the tubes of section 18A in parallel flow with respect to the steam, thence pass through gas chamber 31 and across the lower ends of the tubes of group 18A again in counter flow with respect to the steam flow.

Above superheater section 19A is a baffle 32 which baffle extends from baffle 9 over section 19A at a level above the tubes of section 16. In this way any gas that is by-passed through the boiler bank 5 is forced to pass above the top of the superheater and out of contact therewith. In the conventional arrangement of our parent Patent 2,403,237 (Fig. 1 thereof) the by-passed gases flow over the superheater sections 16, 18 and thence into the by-pass so considerable superheat is generated, which tends to minimize the control of superheat through by-passing the gases because the rate of heat transfer at this point in the superheater is still relatively high; or an excessive amount of gases must be by-passed to obtain the desired control. According

to the improved arrangement shown in Figure 1 hereof, these objections are completely overcome. It is an advantage to by-pass the gases coming from the top of the furnace rather than from a point lower down in the furnace since the gases that reach the top of the furnace have given up more of their heat to the furnace tubes and are relatively cooler thereby resulting in less heat to be absorbed in the by-pass and less severe service on the baffles, dampers etc.

A further advantage of our arrangement of Figure 1 hereof is that the by-pass damper 20 is located at a lower point of the tube bank and baffle 10 extends downwardly across the bent parts of the tubes, as shown at 10A, in the lower part of the bank so as to direct the gases downwardly into the stream from the superheater pass. The gases leaving the by-pass may be hotter than those leaving the superheater and by this arrangement intermingle with the latter below the tubes of the banks and pass over the bottom ends of the tube bank to be thoroughly mixed so as to enter the economizer (see device 8 of our parent Patent 2,403,237) at a uniform temperature. This distinguishes from the arrangement shown in our parent Patent 2,403,237 (Fig. 1 thereof) where because the gases flow through a shorter by-pass with less heat absorbing surface they leave and are then directed upwardly into one part of the economizer which is therefore in danger of becoming overheated.

In the modification shown in Figure 2 hereof, some of the furnace tubes 12 which form the support of the baffle 28 between the furnace and the superheater, pass between the superheater sections 18B and 19B. The path of steam flow through the tubes as shown by the arrows is somewhat different from that in Figure 1 with the result that the gases flow across the tubes of section 19B in counterflow with respect to the steam as in Figure 1 thence across the upper portion of the section 18B in counterflow instead of parallel as in Figure 1 and thence across the lower portion of section 18B in parallel flow rather than counterflow as in Figure 1. Obviously additional superheater sections may be added in additional passes wherein the steam flow will be generally counter to the gas flow.

While several modifications of the invention have been illustrated and described in detail it is to be understood that the invention is not limited to the precise forms or arrangements shown but comprehends other alternatives and mechanical equivalents of the apparatus herein illustrated and falling within the scope of the appended claims.

What we claim is:

1. A steam generator comprising a water-cooled furnace with a gas outlet near its upper end; a steam superheater located adjacent to and in communication with the gas outlet and below the plane of the furnace roof including a multiplicity of parallel tubular fluid heating elements each comprised of substantially vertically disposed tubes interconnected by return bends to form a continuous path for steam flow; means at the lower end of said superheater con-

stituting a path for discharge of said furnace gases after heat-imparting contact with said superheater tubes; means forming a by-pass around said superheater to by-pass part of the furnace gases and leading into the said superheater tubes' gas discharge path, said by-pass means comprising a rear wall that is separated from said superheater by said by-pass; a control damper at the outlet end of said by-pass and hingedly mounted at a point intermediate the said by-pass outlet and the lower end of said superheater and at a point remote from said rear wall; heat absorbing surface arranged in the by-pass and comprising a substantially vertically disposed bank of steam generating tubes having a lower portion extending below the elevation of the by-pass damper into the aforesaid discharge path of gases from said superheater and said by-pass; and baffle means extending from the lower end of said rear wall across the by-pass heating surface tubes above said discharge path and above said lower steam generating tubes portion to require flow of the by-pass gases past said damper so that when the damper is opened the gases from the superheater pass and those from the by-pass are mixed and subsequently passed over the surface of the said lower steam generating tubes portion.

2. A steam generator comprising a vertically elongated furnace with a lateral gas outlet at its upper end for discharging hot combustion gases, said lateral outlet including means forming an upper gas flow path and a lower gas flow path parallel therewith, said lower gas flow path having a downwardly extending first gas flow pass subjoined thereto; a multiplicity of tubular superheater elements located within said lower parallel flow path and extending thereacross to establish cross flow of said combustion gases therover; means forming a by-pass around said superheater for said furnace gases, said by-pass including said upper gas flow path and a downwardly extending second gas flow pass subjoined thereto; steam generating tubes in said second pass; and a control damper at the outlet of said by-pass and associated with both said first and second gas flow passes to proportionately distribute furnace gases flowing over the steam generating tubes through said by-pass and over said superheater elements.
